UNITED STATES PATENT OFFICE.

WALTER S. ROCKWELL, OF NEW YORK, N. Y., ASSIGNOR TO W. S. ROCKWELL COMPANY,
OF NEW YORK, N. Y., A CORPORATION OF NEW JERSEY.

FURNACE.

1,177,058.

Specification of Letters Patent. Patented Mar. 28, 1916.

Application filed July 28, 1915. Serial No. 42,270.

To all whom it may concern:

Be it known that I, WALTER S. ROCKWELL, a citizen of the United States, residing at 300 West One Hundred and Sixth street, 5 New York, county of New York, and State of New York, have invented certain new and useful Improvements in Furnaces, fully described and represented in the following specification and the accompanying drawings, forming a part of the same.

This invention relates to that class of furnaces employed in heating objects of any desired character, as in the operations of annealing, hardening, coloring, tempering, 15 reheating, forging, &c., and the improvements consist in the construction hereinafter described and claimed. In such furnaces, the charge of material or articles to be treated is placed upon the working-floor of 20 a chamber in which the heat is applied to the objects, and which will be called the "heating-chamber" herein. Such heating-chamber receives the heated gases from a chamber in which solid, liquid or gaseous 25 fuel is burned, and this latter chamber is termed the "combustion-chamber" herein.

The passages for the entrance of the heated gases, and the escape of the waste gases, are located at the side of the heating-chamber; 30 and an additional advantage is secured by forming a ledge at one or each side of the heating-chamber, through the top of which such passages are extended, as such ledges provide a space at the edge or edges 35 of the working-floor for the circulation of the heated gases at the side or sides of the charge. With escape outlets near the floor level, the constant inflow of heated gases forces the burnt gases to move gradually 40 downward from the roof of the heating-chamber to the floor of the same before they can escape from the heating-chamber. Both sides of heating-chamber are formed with a series or plurality of inlet and outlet-passages so that both edges of the charge upon 45 the working-floor of the chamber are equally heated. The forced downward movement of the gases brings them positively into contact with the charge and causes them to 50 thoroughly heat the same in all parts alike

as they pass to the outlet-passages adjacent to the edges of the working floor. The openings of the inlet and outlet passages are arranged alternately in the length of the ledge, so that the currents of heated 55 gases which rise from the inlet-passages are more or less mixed with the descending body of burnt gases moving toward the outlet-passages in the same ledge. The location of the inlet-passages in the top surface of 60 the ledges causes the heated gases to move upward as they enter the heating-chamber, and thus prevents their overheating the edges of the charge upon the working-floor. The location of the outlet passages in the 65 edges of the floor avoids the formation of so-called "short-circuits" of gases in the heating-chamber, which arise when the heated gases are admitted in the lower part of the chamber and are wasted by discharge 70 into the air from the upper part, as in such case the hot gases naturally tend to rise without stratification and escape from the upper outlet without effectively heating the charge upon the working-floor. 75

The completeness with which the gases are mixed in the present construction, and their retention in the chamber and upon the charge as they move downwardly and enter the outlet passages, operates to utilize 80 the heat in the most efficient manner. A greater effect or penetration of the heat is produced by the pressure of the accumulated gases in the heating-chamber, which thus operate uniformly upon the heated 85 charge.

The invention will be understood by reference to the annexed drawing, in which—

Figure 1 is a longitudinal vertical section at the middle of the furnace; Fig. 2 is a 90 plan in section on line 2—2 in Fig. 1; Fig. 3 is a section on line 3—3 in Fig. 2; and Fig. 4 is an elevation of the furnace at the end having the door; Fig. 5 a section on line 5—5 in Fig. 6. Fig. 6 is a plan of an 95 alternative construction partly in section.

In Figs. 1 to 3 *a* designates the side-walls of the furnace, *b* the rear wall, and *c* the front-wall having the door-opening; *d* provided with door *d'*. A door opening is 100

shown at one end of the heating-chamber, but the door-openings may be made in both ends of the furnace if desired, and are preferably made narrower than the space between its side-walls, which contains the chamber-floor. The floor of the heating-chamber is shown provided with ledges *e* next the side-walls, between which ledges the space may be considered as the "working-floor", as the "charge" is confined to such space by the upward projection of the ledges.

Two combustion-chambers *g*, *g'* are shown beneath the floor of the heating-chamber and supplied with burners *h*, *h'*, for gas or oil. Any other suitable fuel may be used, as coal burned upon a grate. These combustion-chambers are used simultaneously and not reversibly. An outlet-flue *i* for the waste gases is extended lengthwise of the furnace under the combustion-chambers, and outlet-passages *k* are shown extended through the ledges and through the floor into connection with the outlet-flue *i*, as per arrows *n'*. Inlet-passages *l* extend from the combustion chambers upward through the main floor and the ledges, and introduce the heated gases into the lower side of the heating-chamber, as indicated by the arrows *n*.

Holes *m* are shown extended through the arches (over the combustion-chambers) which form the working-floor of the heating chamber, to distribute a proportion of the heated gases to the bottom of the charge when the nature of the charge requires. The entire space between the side-walls of the heating-chamber, which includes the working-floor and the space occupied by the ledges, may be termed the "main-floor" of the heating-chamber through which the heated gases are introduced, and the spent gases escape.

The working-floor is shown in Fig. 3 having the usual iron T-bars *e* partly sunken in the material of the floor to support the pans, ingots or other charge a little above the floor, so as to permit the access of the gases through the holes *m*, and their circulation beneath the charge, when the heating chamber is charged.

A damper *h*⁴ in the form of a sliding gate is shown applied to the outlet flue to regulate the discharge of the spent gases.

The operation of the furnace is as follows:—Combustion being effected in the combustion chambers, the heated gases of combustion rise upwardly through the holes *m* and the inlet passages *l* to generate the desired temperature in the heating chamber. The heated gases naturally rise to the top *f* of the heating chamber, where their accumulation forces the gases downward in strata toward the working-floor *e* until the

gases reach such floor, and the charge upon it, and are forced into the outlet passages *k*. As the inlet-passages introduce the heated gases at both sides of the heating-chamber, an equal temperature is produced upon both edges of the charge upon the working floor. The location of the outlet passages close to the floor level compels such downward movement of the heated gases and their pressure upon the charge before they can escape. Any accumulation of soot or dirt in such passages can be readily cleaned out through apertures *k'* in the side wall of the furnace, which apertures are closed by plugs *k''*.

It will be noted that the passages *k* and *l* in Figs. 1 to 3 are not formed in the side-walls of the furnace, and do not therefore weaken the side-walls, as is common in many prior constructions; but the inlet-passages are formed solely through the main-floor of the heating-chamber and the ledges upon it; and the outlet-passages are conducted through the ledges to the outlet-flue. Such outlet-passages are shown extended through the edges of the main-floor, to reach the outlet-flue *i*.

When properly heated, the floor is charged with the material to be treated, the temperature being regulated by the damper *h*⁴, which is operated to control the flow of spent gases from the heating-chamber as may be required.

An alternative is shown in Figs. 5 and 6, to illustrate a construction for the outlet-passages, where the flue for waste-gases passes upward or horizontally from the body of the furnace. The section at the right side of Fig. 5 shows the inlet-passage *l*, connected with a combustion-chamber under the floor of the heating-chamber, and heated by burners *h*³. Such inlet extends directly through the floor of the heating-chamber as in Fig. 3, but the outlet *k* extends downward through the ledge for a sufficient distance below the level of the working-floor *e*, to permit the extension of a lateral passage *k*³ to connect with an uptake *p* in the side-wall of the furnace. The upper edge of the passage *k*³ is represented slightly below the level of the working-floor *e*, so that the gases cannot escape to the uptake *p* until sufficient pressure is developed in the heating-chamber to force the waste-gases downward to the level of the working-floor. This secures a heating of the working-floor or any charge laid upon it, while it permits the waste-gases to be discharged laterally or upwardly from the lateral passages *k*³. A damper *h*⁵ may be applied to each of the uptakes, as shown.

One advantage of the use of the ledges is that the floor cannot be so loaded as to prevent the circulation of the gases between the side-walls and the material charged upon the working-floor.

The discharge, by the outlet-passages, below or at the level of the working-floor produces a gas-pressure upon the floor and upon the articles which may be disposed upon the floor, thus insuring a more uniform heating of the articles. Such outlet-passages also maintain the required heat near the door of the chamber, by reason of the gas-pressure which is generated and maintained therein.

10 They also admit of a stronger structure, with facility for cleaning the passages.

It will be understood that the peculiar arrangement of the outlet-passages operates, conjointly with the arrangement of the inlet-passages at the same level, to produce a heating of the working-floor (or of the charge laid upon it) by actual contact of the heated gases. To produce a uniform heating of the chamber and the charge therein, the heated gases are introduced through a series of inlet-passages at both sides of the chamber, and at or close to the floor-level; and it will be understood that these inlet-passages operate to continuously and 25 simultaneously deliver the heated gases to both sides of the chamber, while the outlet-passages operate to continuously remove the spent gases therefrom.

In my construction, the heated gases are 30 continuously introduced through the same passages, and the same outlet-passages also serve continuously to discharge the spent gases from the chamber.

It will be observed that the inlet and 35 the outlet-passages are arranged alternately along the sides of the working-floor (in the ledges), and produce a plenum or pressure of the gases within the chamber. Such plenum is a necessary result of the gas-outlets being at the bottom of the heating-chamber, as the gases would not pass from the outlets in such a location until a gas-pressure was generated in the chamber and upon the charge.

40 45 It will be understood that as the incoming heated gases are lighter than the outgoing gases partly cooled, they force themselves upward through the descending body of gases in the chamber, and thus secure a very even distribution of the heat. Such thorough mixing is produced by the travel of the gases from the bottom of the chamber to the top and back again, and a perfectly uniform pressure in the chamber is also 50 produced because no outlet exists intermediate to the top and bottom to relieve the pressure above the level of the working-floor.

A series or plurality of inlet and outlet 60 passages along both the side-walls of the chamber is desirable in the present invention, to diffuse the heated gases throughout the chamber as they enter the same, and also to withdraw waste gases from numer-

ous points in the chamber so as to avoid any 65 draft of the heated gases to any particular point.

The location of the outlet passages at substantially the level of the working floor, and their arrangement alternately with the inlet 70 passages, gives them such a relation to the inlet passages and to the working floor as to produce a satisfactory action of the heat upon the charge, which is greatly affected by the heated gases being forced or built 75 downwardly in strata from the roof of the heating chamber into contact with the charge. The movement of the gases upward and downward between the floor and the roof of the heating chamber, secures a 80 most effective circulation of the gases adjacent to the sides of the charge upon the floor, and secures an equal heating of the charge, which would be less effective with a charge lying close to the side walls of a 85 furnace without such ledges and passages.

It has been found by experience that slight changes in the disposition of the inlet and outlet-passages make a very material difference in the operation of a furnace, 90 and many furnaces operate inefficiently because the heat is not properly distributed. My disposition of the inlet and outlet-passages has been found in practice to produce a most uniform effect of the heat upon the 95 charge, and to secure a rapid heating of the charge in the heating-chamber and a maintenance of the heat in an economical manner.

Having thus set forth the nature of the 100 invention what is claimed herein is:

1. A furnace having a heating-chamber with a ledge along the wall upon at least one side of the chamber, a combustion-chamber with a series of inlet-passages for supplying heated gases from the same to the heating-chamber through the said ledge and a series of outlet-passages extended from the heating-chamber through the same ledge, whereby inlet and outlet-passages in 105 the same ledge operate respectively to simultaneously introduce the heated gases to and remove the spent gases through the same ledge in the heating-chamber.

2. A furnace having a heating-chamber 110 with ledges disposed upon the floor of the heating-chamber along its walls, means for supplying heated gases simultaneously through inlets in the said ledges, and a plurality of outlet-flues in the ledges operated 115 continuously and simultaneously to remove the spent gases from the heating-chamber.

3. A furnace having a heating-chamber with ledges disposed upon the floor of the heating-chamber along the walls of the 120 same, a combustion-chamber with a series of inlet-passages extended through the said ledges for supplying heated gases from the

same to the heating-chamber, a series of outlet-passages extended through the said ledges and disposed alternately therein with the inlet-passages, the inlets and outlets operating respectively to continuously and simultaneously deliver the heated gases to

and remove the spent gases from the heating-chamber.

In testimony whereof I have hereunto set my hand in the presence of two subscribing 10 witnesses.

WALTER S. ROCKWELL.
